(57) **CLAIM**

The ornamental design for an adjusting knob for a scope, as shown and described.

DESCRIPTION

FIG. 1 is a front/right isometric view of an adjusting knob for a first embodiment of a scope;

FIG. 2 is a front view of the adjusting knob of FIG. 1;

FIG. 3 is a rear view of the adjusting knob of FIG. 1;

FIG. 4 is a right side view of the adjusting knob of FIG. 1;

FIG. 5 is a left side view of the adjusting knob of FIG. 1;

FIG. 6 is a top view of the adjusting knob of FIG. 1;

FIG. 7 is a bottom view of the adjusting knob of FIG. 1;

FIG. 8 is a front/right isometric view of an adjusting knob for a second embodiment of a scope;

FIG. 9 is a front view of the adjusting knob of FIG. 8;

FIG. 10 is a rear view of the adjusting knob of FIG. 8;

FIG. 11 is a right side elevational view of the adjusting knob of FIG. 8;

FIG. 12 is a left side elevational view of the adjusting knob of FIG. 8;

FIG. 13 is a top view of the adjusting knob of FIG. 8; and,

FIG. 14 is a bottom view of the adjusting knob of FIG. 8.

The broken lines in the drawings are used to illustrate the environment of the invention and they do not form any part of the claimed design.

1 Claim, 8 Drawing Sheets
